UNITED STATES PATENT OFFICE.

WILLIAM K. BENEDICT, OF NEW YORK, N. Y., ASSIGNOR TO THE CO-OPERATIVE BUILDING PLAN ASSOCIATION, OF SAME PLACE.

DESIGN FOR THE EXTERIOR OF A RESIDENCE.

SPECIFICATION forming part of Design No. 19,546, dated December 31, 1889.

Application filed December 7, 1889. Serial No. 332,972. Term of patent 3½ years.

To all whom it may concern:

Be it known that I, WILLIAM K. BENEDICT, of the city, county, and State of New York, have invented and produced a new and original Design for the Exterior of a Residence, of which the following is a specification, reference being had to the accompanying drawings, forming a part thereof.

Figure 1 represents a perspective view of a residence showing my design. Fig. 2 represents a horizontal section or plan of the first story. Fig. 3 represents a horizontal section or plan of the second story.

Similar letters of reference designate corresponding parts in all the figures.

A residence embodying my design is generally rectangular in the ground plan, and comprises a first and second story and an attic story, the attic story being beneath the gable roofs.

The front of the first story is illustrated as having an octagonally-shaped bay A. At one side of the octagonally-shaped bay A is a porch B, to which a flight of steps a leads. The side of the residence beyond the porch B is for a distance substantially flat, but beyond said flat portion an L C extends. A flight of steps b leads to a doorway b', opening

into said L. At the rear of the first story is an octagonally-shaped bay D and a porch E, 30 to which a flight of steps e leads.

The second story is illustrated as having at the front a projecting rectangularly-shaped bay E. Consoles f extend between the bay F and the bay A. Machioolations are illustrated as between the consoles f. The side of the residence is illustrated as having an upward extension of the L, such extension being lettered G. The extension G above the portion C thereof is surmounted by a gable 40 roof H. The main portion of the residence is surmounted by a gable roof I. Upon the gable roof I are two dormer-windows J J', each surmounted with hipped roofs.

Above the bay F and at the attic story said 45 bay is surmounted by a gable roof K. Projecting from the gable of said roof is a bay L, below which are consoles l.

What I claim is—

A design for the exterior of a residence, 50 substantially as herein shown and described.

WILLIAM K. BENEDICT.
